UNITED STATES PATENT OFFICE.

JOHN HERMAN, OF LOS ANGELES, CALIFORNIA.

SCREENING TUBE-MILL.

1,176,896.

Specification of Letters Patent. Patented Mar. 28, 1916.

Application filed May 9, 1914. Serial No. 837,403.

To all whom it may concern:

Be it known that I, JOHN HERMAN, a citizen of the United States, residing at Los Angeles, in the county of Los Angeles and 5 State of California, have invented a new and useful Screening Tube-Mill, of which the following is a specification.

My invention relates to tube mills in which the ore or other material is ground 10 by pebbles or other hard substances and discharged through a screen or openings of desired areas.

The object of the invention is to provide simple and effective means for grinding 15 and promptly removing the pulverized ore from the machine when it has attained the desired fineness. The unnecessary retention and comminution of ore requires a mill of larger capacity than needed as well as extra 20 power besides putting the ore in the condition known as slime, which is objectionable in some processes of ore treatment. My invention is intended to remove these difficulties and herein consists the principal value 25 of the invention, though the lifting and consequent mixing of the charge, instead of allowing it to slide, is also beneficial in grinding and in protecting the wearing surface of the shell. I attain these objects by 30 the mechanism illustrated in the accompanying drawings in which—

Figure 1 is a side view of the entire machine; Fig. 2, a longitudinal half section of the machine; Fig. 3, an end view of the 35 machine; Fig. 4, a transverse section of the machine.

Similar letters refer to similar parts throughout the several views.

Fig. 1 shows the tube or drum mounted 40 on bearings which are hollow trunnions. The letter *s* indicates the screen closely fitted around the drum horizontally; *bb*, bolts attached to bands to draw the screen closely around the drum; *b*, bolts which 45 pass through the ends of the bars which form the shell of the tube or drum and through flanges on the heads of the drum; *t*, hollow trunnions on which the drum revolves; *p*, a pulley which is secured to an 50 extension of one of the hollow trunnions.

Fig. 2 is an end view of the machine, the ends of the bars being indicated by the letter *g*; the letter *t*, indicates one of the hollow trunnions; *b*, indicates the bolts which pass 55 through the ends of the bars and the flanges on the head of the tube or drum; *bb*, indi-

cates a bolt fastened to a band to keep the screen close to the drum, the band being adjacent to the screen and not shown on account of its small cross section, being al- 60 ready shown in Fig. 1.

Fig. 3 is a longitudinal half section on the dotted line shown in Fig. 2; the letter *g*, indicates the bars which form the shell of the tube or drum, the bars having de- 65 creasing openings between them, the larger areas of the openings being on the inside of the shell; *b*, indicates the bolts which pass through the bars and the flanges on the head of the tube or drum; *t*, indicates the 70 hollow trunnions one of which is extended to carry the pulley which is indicated by the letter *p*; *s*, indicates the screen.

Fig. 4 is a transverse section on the dotted line shown in Fig. 1. The letter *g* indicates 75 the bars, two bars constituting a single casting, which casting is indicated by the letter *g*, in Fig. 2; *s*, indicates the screen; *t* shows the opening through the hollow trunnion at the farther end of the tube or drum. 80

In operation, flint pebbles or other hard substances of suitable shape and size are put into the mill to grind the ore, which is fed into the mill preferably through hollow trunnions. The tube or drum is revolved at 85 a suitable speed. The decreasing openings prevent coarse particles from reaching the screen while any material remaining in the openings will drop down into the charge when the bars are at the higher points. 90 The constant movement of the pebbles or balls causes vibrations of the shell which are imparted to the screen which is in close contact with the outside of the shell, thus aiding gravity in keeping the screen open- 95 ings from clogging. Where ordinary shaking screens may have two or three jars a second my machine has as many hundred in the same time, thus keeping the screen clean. 100

The openings of continuously decreasing area in the bars prevent the coarse pieces from reaching the screen, thus preventing injury thereof; these openings also allow the coarse pieces referred to to be carried up 105 to the upper part of the drum and to fall down into the charge as the mill revolves and to be reground until fine enough to pass out the screen or through the external openings of the bars if no screen is used on 110 the mill.

The drawing shows the preferred form

of the mill and the component parts of the preferred form but I do not limit myself to the form or shape of the mill or its parts as shown therein.

5 It is of importance that the openings from the inside of the shell toward the outside are made of continuously decreasing cross sectional area in order that any particles of ore, such as quartz ore, which have a 10 tendency to become lodged in these openings, may be dislodged and made to fall back into the grinding zone as the shell revolves. Such action is facilitated by the vibration caused by the grinding balls or 15 pebbles. The mill is especially valuable in concentrating ores, which will be thoroughly disintegrated to the size desired and wholly discharged from the mill.

I claim:

20 1. A grinding and screening mill comprising a rotatable tube or drum horizon-

tally mounted and having openings of continuously decreasing cross sectional area in the shell with the larger area of the openings inside said shell, grinding means in 25 said drum, and a continuous screen circumferentially mounted on the outer periphery of said drum, substantially as described.

2. A grinding and screening mill comprising a rotatable tube or drum horizontally mounted, the shell of which is made of bars, the area between the bars continuously decreasing in cross section from the inside, the spaces between the bars on the outside 30 being of suitable width to screen the pulverized material to the desired fineness, and grinding means in said drum, substantially 35 as described.

JOHN HERMAN.
